EMORY C. HISCOCK, OF CHICAGO, ILLINOIS, ASSIGNOR TO W. W. KIMBALL COMPANY, OF CHICAGO, ILLINOIS, A CORPORATION OF ILLINOIS.

SELF-PLAYING PIANO.

No. 920,954.

Specification of Letters Patent.

Patented May 11, 1909.

Application filed September 25, 1908. Serial No. 454,767.

To all whom it may concern:

Be it known that I, EMORY C. Hiscock, a citizen of the United States, residing in Chicago, in the county of Cook and State of Illinois, have invented a new and useful Improvement in Self-Playing Pianos, of which the following is a specification.

In the ordinary construction of self playing pianos, the wind producing devices and reservoir of pneumatic actions are generally located below the key desk and either require an enlargement of the piano case or are placed in front of the lower ends of such of the strings as extend below the key board. It is of course not desirable to enlarge the case, and the location in front of the strings is not only not convenient of access, but it is objectionable for the further reason that the devices mentioned muffle the sound of the strings, and must be removed whenever access to the strings becomes necessary or desirable. I remove these objections, by arranging the feeders and the reservoir of the action in horizontal position side by side, within the bed rail of the key desk, where they occupy no room except such as has heretofore been vacant, and are easy of access for repairs, and leave the sounding strings below the keys wholly uncovered. The nature of my improvement is fully disclosed below, and also illustrated in the accompanying drawing, in which latter—

Figure 1 is a vertical section of a piano embodying my invention. Fig. 2 is a bottom plan of the bed rail of a piano key desk, in which my invention is arranged. Figs. 3 and 4 are sections on the lines 3—3 and 4—4 respectively of Fig. 2.

In said drawing, 10 represents the bed rail of a piano key desk. As usual, it consists of a rectangular frame, the long front and rear members of which are connected and braced at intervals by cross pieces 11. It is also provided with a covering 10^a. In two adjacent spaces formed between the cross pieces, I place the feeders 12, 12, in horizontal position with their movable boards 13 on the under side so they can be connected directly to the pedals 14 by straps 15 and 16 which are united as in Fig. 1. These feeders unite in maintaining exhaust pressure in the channel 17 which connects them with the pneumatic action of the instrument and the

reservoir 18. The latter is also arranged in a horizontal position alongside one of the feeders and in an adjacent open space within the bed rail. The feeders and reservoir are of the usual construction, except so far as they are changed to adapt them to use in horizontal positions, the former having the usual springs 19 tending to collapse them, and the latter having an expanding spring 20 mounted on one of the cross pieces 11 and bearing on a lateral arm of the bottom of the reservoir. I also place within the bed rail adjacent to the reservoir, a device for cutting off the exhaust from the action during the rewinding, consisting of a valved pneumatic 23. This pneumatic cuts off the exhaust through channel 24 leading from the action. I also place within the bed rail space, pneumatic governor devices, and locate them at the right hand end of the key bed as shown in Fig. 3. As such governing devices form no part of the present invention, I do not describe them herein, but it will be understood that the necessary air-channels connecting the action and the music sheet operating devices with the feeders and reservoir are also located as far as possible, within the bed rail space.

I claim:—

1. A self playing piano having its exhaust wind producing feeders and their connecting air channels located within the bed rail of the key desk.

2. A self playing piano having its exhaust wind producing feeders and reservoir, and the air passages connecting them with the action, all located within the bed rail of the key desk.

3. A self playing piano having its exhaust wind producing feeders and reservoir arranged horizontally, the feeders, reservoir and the connecting air passages being all located within the bed rail of the key desk.

4. A self playing piano, having its exhaust producing feeders arranged horizontally within the bed rail of the key desk of the piano, and also having pedals for operating said feeders connected to the underside thereof.

EMORY C. HISCOCK.
